Application January 12, 1949, Serial No. 70,403

6 Claims. (Cl. 68—25)

1

This invention relates to commercial laundry machines and more particularly to a commercial laundry machine of the type wherein a container for the work to be laundered is rotatably mounted in a shell and both the shell and the container are movable from a horizontal washing position to a vertical extraction position.

As is well known, the combination of a washer and an extractor in such a manner that the washing and the extracting may be carried out in the same container by changing the position of the axis thereof has the advantage of rendering unnecessary the transfer of the water-soaked clothes from one place of the laundry to another place, the weight of such water-soaked clothes amounting in commercial washers ordinarily to several hundred pounds.

Such machines have not come into use because when the container is moved to the extracting position, the load is not as well distributed as in an extractor when packed by hand. Hitherto this unbalance has created such excessive vibration during the extraction as to prevent the use of such apparatus.

The invention makes it possible to extract in the same container in which the clothes have been washed by first reducing the amount of unbalance by dividing the load into two lots separated by a diametral partition in the container, then by aiding the distribution of the load about the axis through draining off the pool in which washing has taken place only after the container has reached extracting position, and finally by providing a suspension that absorbs the vibration created by the remaining unbalance.

In the preferred operation of the apparatus, the container is repeatedly moved from one position to the other and to facilitate this the container is made to tilt about an axis that is located to one side of the extraction spindle, passing close to the center of gravity of the container and its load.

An object of the invention is to provide a laundry machine of the type referred to which has the shell and the container mounted on a laterally movable platform which supports the shell and the cylinder both in their horizontal washing position and in their vertical extraction position.

Another object of the invention is to provide a laundry machine of the type referred to having the shell and container mounted on a platform which, while permitted to sway freely in a horizontal plane, will not be subject to substantial vertical vibrations.

2

A further object of the invention is to provide a laundry machine of the type referred to in which the platform which supports the shell and the container both in their washing position and in their extraction position is linked to a stationary base in such a manner as to be biased to assume a specific position relative to said base from which position it will deviate substantially in a horizontal plane only.

10 A further object of the invention is to provide a laundry machine of the type referred to wherein platform is suspended from columns standing up from a stationary base by means of linking elements permitting a swaying movement of the platform relative to the base and

15 wherein rigidly connected to the platform are supporting means which support the shell and the container both in their washing position and in their extracting position.

20 A further object of the invention is to provide a laundry machine of the kind just referred to wherein the linking elements by means of which the platform is suspended from the columns are attached to arms which are rigidly connected to and extend upwardly from the platform, the points of attachment being situated in a horizontal plane passing through, or close to, the center of gravity of the shell with all parts supported thereby or thereon when the shell is moving from the washing to the extracting position.

25 A further object of the invention is to provide a laundry machine of the type referred to wherein the shell together with the parts carried thereby is supported in the horizontal position as well as in the vertical position on three points rigidly secured to the platform, two of these three points remaining the same for both positions whereas the third point of support, for supporting the shell when in the horizontal position, is different from the third point of support for supporting the shell when in the vertical position.

30 Another object of the invention is to provide a laundry machine of the type referred to wherein the container is divided into separate compartments which are accessible through doors in an end wall of the container and in an end wall of the shell.

35 A further object of the invention is to provide 45 hydraulically operated means for opening and closing the door or doors in the end wall of the shell.

40 Still a further object of the invention is to provide pivotal supports for the shell on a horizontal axis extending to one side of the axis of the shell and approximately in the horizontal

plane in which the center of gravity of the shell and all parts carried thereby is located when the shell is in the extraction position.

Another object of the invention is to provide in that end wall of the shell, which in the vertical position of the latter forms its bottom wall, an outlet opening permitting the draining of the shell when this shell is in the vertical extraction position but being in an ineffective position for draining when the shell is in the horizontal position.

Another object of the invention is to provide a highly economical method for operating a laundry machine of the type wherein a container for the work to be laundered is rotatably mounted in a shell and both the shell and the container are movable from a horizontal washing position to a vertical extraction position. In commercial washing it is generally necessary to apply in succession a plurality of suds treatments and of rinsing operations to the same lot of material to be cleansed. With this in view, the invention contemplates the application of the suds and rinsing treatments in such a way that the shell and container are tilted from the horizontal washing position to the vertical extraction position each time a suds or rinsing treatment is completed and to allow the spent liquid to drain off when the shell and container are in the vertical position.

Other objects and advantages of the invention will appear as the description proceeds, reference being had to the accompanying drawings which, by way of example, show one embodiment of the invention. In these drawings:

Fig. 1 is a side elevation of the machine in position for loading or extracting;

Fig. 2 is a side elevation of the machine in the act of passing from the extraction position to the washing position;

Fig. 3 is a vertical section of the machine in the position for washing;

Fig. 4 is an end view of the machine when the same is in washing position, one of the housing doors and the columns being shown partly broken away; and

Fig. 5 is a plan view of the machine in position for extracting.

Connected to a stationary base 11 in such a manner as to be able to perform lateral movements relative to this base is a platform 12, preferably of generally rectangular form. The base 11 carries three columns or pedestals 13, each having its upper portions so shaped as to form a cap 14 and a horizontal wall 15. Each horizontal wall 15 serves as a support for a bolt 16 secured by lock nuts 17 and carrying a chain 18 whose lower end carries a bolt 19 with lock nuts 20. The three chains 18 carry by means of their bolts 19 and nuts 20 the platform 12 which has three upstanding arms 21 each provided at or near its upper end with a hole 22 through which the coordinated bolt 19 passes. Due to the connection just described, the platform 12 is free to perform swaying movements relative to the stationary base 11.

The platform 12 supports the combined washing and extracting machine which has a cylindrical shell 23 and, rotatably mounted therein, a perforated cylinder 24. In order to support the shell 23, there are provided on the platform 12 two posts 25 each carrying at its upper end a bearing 26. The two bearings 26 support each one of two coaxial trunnions or studs 27 attached to the shell 23 by means of brackets 28. The shell 23, together with all the parts mounted thereon and

therein, can thus be turned about the axis extending through the two trunnions 27 which axis extends at a right angle to the axis of the shell 23 at a distance therefrom and which is indicated in Fig. 3 at 29. That one of the three upstanding arms 21 of the platform 12 which is visible in Figs. 1, 2 and 3 is provided with a seat 30 on which the shell 23 rests when the machine is in the vertical extraction position shown in Fig. 1. The platform 12 further carries by means of brackets 31 a cross bar 32 on which the shell 23 rests when it is in its horizontal washing position shown in Figs. 3 and 4. Thus, the shell 23 together with the parts carried thereby is supported in the washing position as well as in the extracting position by the platform 12 on three points, of which three points two, namely the bearings 26 carried by the two posts 25, remain stationary for both the horizontal washing position and the vertical extracting position of the machine, whereas the third point of support is the cross bar 32 for the washing position and the seat 30 on the one platform arm 21 for the extracting position.

The upper ends of the three upstanding arms 21 of the platform 12 are situated in a horizontal plane which is also the plane in which, or close to which, the center of gravity of the platform and all the parts carried thereby, such as the shell 23, the cylinder or basket 24 and the load placed in this basket is situated when the shell and basket are in vertical position. Also located in this plane is the axis 29 of the trunnions 27 about which the shell 23 and all parts carried thereby are tiltable. Due to this location of the points at which the platform 12 is attached to the linking elements 18 the construction is such as to readily absorb vibrations and to avoid any substantial vibrations in vertical direction.

That end of the shell 23, which forms the top end thereof when the machine is in the extraction position shown in Fig. 1, is permanently closed over one-half of its surface by a semi-circular wall 33, whereas the other half of this end is openable and closeable by means of two quadrant shaped doors 34 and 35. Attached to the door 34 is a plate 36 which is turnably mounted on a pivot 37 supported by the stationary wall 33. The plate 36 terminates in a toothed segment 38. To the second quadrant door 35 there is attached a plate 42 which is turnable about a pivot 43 and is provided with a toothed segment 44. Meshing with the two segments 38, 44 are two racks 40 and 41 which are carried by a rod 46 connected to a moving mechanism. This moving mechanism is shown in the drawing as comprising a hydraulic ram engine 47 also supported by the stationary shell wall 33. When the pistons in the ram engine 47 move inwardly or outwardly, the two racks 40 and 41 on the rod 46 turn the segments 38 and 44 and thereby open or close the two quadrant doors 34 and 35.

The cylinder or basket 24 within the shell 23 comprises a perforated side wall 48, end walls 49 and 50 and a partition wall 51, the latter containing the rotational axis of the basket so as to divide the basket into two semi-cylindrical compartments 52 and 53. The compartment 52 is accessible through a door 54 hinged at 55 for opening and closing an opening 56 in the end wall 50 whereas the compartment 53 can be reached through a door 57 carrying a latch 190. The door 57 is hinged at 58 and is adapted to open or close an opening 59 in the end wall 50.

The basket 24 is keyed at 99 to the shaft 60.

for rotation therewith. The shaft 60 is supported in two bearings 61 and 62 which are carried by a bearing housing 63 supported on the bottom 64 of the shell 23. The basket shaft 60 extends outwardly beyond the bottom 64 of the shell 23 and carries on this extended end a pulley 65 which is provided with a braking surface 66 and a drive belt surface 67. A belt 68 passes over the surface 67 of the pulley 65 and over another pulley 69 on the driving shaft of the motor 70. The motor 70 which is mounted on the shell 23 by means of a bracket 71 is a high speed motor for imparting to the basket 24 the high extraction speed and it is preferably connectable with the shaft 60 of the basket 24 by means providing for either mechanical or electrical slippage as is well known in the art and therefore not illustrated in the drawing.

A second motor 72 is secured to the bottom 64 of the shell 23. The motor 72 drives by means of a belt 73 a pulley 74 supported by a shaft 75 which also carries a worm 76. The worm 76 engages a worm gear 77 mounted on a stub shaft 78 which is supported by a bearing 79 carried by a bracket 80 that extends downwardly (as seen in Fig. 1) from the bottom 64 of the shell 23. The stub shaft 78 is arranged coaxially with the basket shaft 60 and carries a coupling member 81 of a clutch which is denoted as a whole by the reference numeral 82 and whose second coupling member 83 is carried by the basket shaft 60. The two coupling members 81 and 83 of the clutch 82 may be brought in and out of engagement by a shift lever of any desired design, not shown. The motor 72 is provided for revolving the basket 24 at a low speed when the machine is washing. Since it is customary with washing machines to carry out the washing process in such a manner that the cylinder containing the material to be washed is revolved a number of times in one direction and then reversed to revolve in the opposite direction, the motor 72 is preferably designed for such operation. The electrical reversing controls for such a motor are well known in the art and are, therefore, not shown in the drawing.

On the underside of the shell 23 there are provided to the left and to the right of the center two parallel tracks 84 and with each track 84 cooperates a roller 85 carried by a lever 86 which is swingably mounted on a pivot 87 carried by a bracket 88 secured to the platform 12. Each of the two levers 86 has a pin 89 to which is connected a piston 90 moving in a cylinder 91. The two cylinders 91 bear against fulcrums 92 carried by the platform 12. Dashpots comprising cylinders 93 and pistons 94 are provided to prevent a too violent swinging of the shell 23 about the trunnions 27.

For the purpose of discharging liquid from the shell 23 there may be provided in the shell one or more discharge openings. The drawing shows two such openings, the one being indicated at 95 and the other at 96. The opening 95 is provided in the bottom 64 of the shell 23 at such a point that, when the machine is in the washing position shown in Fig. 3, the opening 95 is situated near the top end of the machine, so that no discharge will occur through that opening prior to the machine being turned to the extraction position where the axis of the shell is vertical. The second discharge opening 96 which is normally held closed by a valve 97 is arranged in the cylindrical wall of the shell 23 at a point thereof which is situated in the lower-

most region of the shell when the latter is in the washing position of Fig. 3. Of the two discharge outlets 95 and 96 shown one, preferably the outlet 96, may be dispensed with as will become apparent later.

The machine may be loaded either in the extraction position of Fig. 1 or in the washing position of Fig. 3. In either case the quadrant doors 34 and 35 are opened by supplying fluid pressure to the hydraulic ram 41. This reveals one of the two doors 54, 57 in the end wall 50 of the basket 24. This door, which according to Fig. 3 happens to be the door 54, is opened and half the load of clothes to be washed is placed in the compartment 52 of the basket 24. The door 54 is then closed and the basket is turned for a half turn so that the basket door 57 becomes aligned with the open half of the shell 23. The door 57 is opened and the second half of the load of clothes is placed in the basket compartment 53. Now the basket door 57 is closed and the quadrant doors 34, 35 of the shell 23 are also closed, the latter by operating the ram engine 47.

It will be noted that the arrangement of the doors in the end walls of the basket and shell is advantageous whether the loading is carried out with the axis of the washer horizontal or vertical. When the loading is done in the horizontal position of the machine shown in Fig. 3, then the door which is in alignment with the opening in the shell and wall furnishes in its open position a horizontal support for the clothes to be placed in the coordinated basket compartment. On the other hand, with the shell and basket in vertical position, it is possible to load the machine from an elevated chute or the like.

After the two compartments 52, 53 have been loaded with the clothes to be treated and the doors have been closed as just described, water and detergent have to be supplied to create a pool of liquid in the shell 23 and the basket 24. This is being done with the shell and basket in the horizontal washing position shown in Fig. 3, and if shell and basket are not already in this position for the loading of the basket with the clothes, they have to be brought into this position. This is achieved by applying fluid pressure to the cylinders 91 so that by means of the pistons 90 and the pins 89 the levers 86 are turned in counterclockwise direction (as shown in Fig. 2). The levers 86, by means of their rollers 85, move the shell 23 and the basket 24 from the position shown in Fig. 1 through the position shown in Fig. 2 to the position of Fig. 3. The shell 23 turns thereby about the axis 29 of the trunnions 27. Whereas prior to the beginning of this 90° tilt of the shell 23 the bottom 64 thereof had rested on the seat 30 on the one platform arm 21, at the end of this movement the side wall of the shell 23 settles down on the crossbar 32 carried by the platform 12. However, due to the mounting in the bearings 26 carried by the platform 12, the shell 23 is supported by the platform 12 all the time, that is to say, never leaves this platform.

When the shell is filled with water and detergent up to the desired level, indicated in Fig. 3 at 98, the clutch 82 is closed and the motor 72 started. As the motor 72 is of the reversing type, the basket 24 is caused to revolve alternatingly in one direction and the other at a low speed desirable for washing, such as 25 R. P. M. After the first suds treatment is finished, the dirty water may be drained off through the outlet 96 by opening the dump valve 97. Then, as usual, washing

may be restarted with a new quantity of warm water containing detergent, and, after repeating the suds treatment several times, dumping the used washing liquid after each such treatment, the clothes may be rinsed for a certain number of times with warm water. When all these washing and rinsing steps, which may include also bleaching, bluing, and souring steps, have been carried out and the liquid has drained out through the outlet opening 96, and after the clutch 67 has been opened to cut out the motor 72, the shell 23 together with the basket 24 is, by releasing the fluid pressure in the cylinders 81, allowed to turn into the vertical extraction position shown in Fig. 1. Since the axis 29 about which the shell and the basket turn is situated eccentrically of the axis of the shell and basket, the latter will tend to assume the vertical position of Fig. 1 under their own weight so that the bottom 64 of the shell 23 will come to rest on the seat 30. In this position of the shell 23 the motor 70 is started, throwing the basket 24 into extraction speed, which may be a speed of, e. g., 725 R. P. M. After the extraction has led to the desired degree of removal of the moisture contained in the clothes, the machine is brought to a standstill and the clothes are removed first from the one basket compartment and then from the other. The removal of the clothes is preferably carried out in the horizontal position of the machine. If in this position of the machine the shell doors 34, 35 are opened and the basket 24 is turned so that the partition wall 51 extends in the horizontal plane, then the open door 54 or 57 of that particular basket compartment 52 or 53, which happens to be at this time the upper half of the basket, serves as an apron which permits the comfortable unloading of that particular compartment. This compartment having been unloaded and its door closed, the basket is turned 180° so that the other half of the basket is on top and aligned with the shell opening for being unloaded.

The described machine may be operated in a more advantageous manner which consists in tilting the machine from the position of Fig. 3 to the position shown in Fig. 1 each time one of the suds or rinsing treatments is completed, and to allow the spent washing solution to drain off when, and only when, the shell is in the up-ended position of Fig. 1. This mode of operation permits the attainment of a desired degree of cleanliness with fewer successive suds and rinsing treatments than the previously described method wherein all sudsing and rinsing steps are carried out prior to any extracting operation. From the following example it will be seen how the two methods compare:

If the described machine is loaded with, say, 150 lbs. of soiled clothes, these clothes will absorb more than twice their weight of water so that, upon opening of the drain opening 95, the clothes will weigh more than 450 lbs. after the water not absorbed by the clothes has drained off from the shell. Assuming that in the first suds operation substantially all of the dirt loosens and goes into solution, then of the total amount of water in the container, which comprises that absorbed by the clothes and that forming the pool of the level 98, only one quarter passes out through the valve 97. In other words, if the soil is uniformly distributed throughout the water, as much as $\frac{3}{4}$ of the soil originally present is still present after draining after the first suds treatment has been completed. If the shell is now refilled with washing liquid up

to the level 98 and the clothes are subjected to a second washing operation whereupon the valve 97 is opened again, there will remain in the clothes $\frac{1}{4}$ or approximately $\frac{1}{2}$ of the soil which was originally present. After the third suds treatment, followed by dumping, there will be left in the material to be cleansed $\frac{7}{16}$ of the original soil and the fourth treatment will leave retained in the clothes $\frac{1}{16}$ or about $\frac{1}{3}$ of the original soil. Thus with this washing method, which is substantially the conventional method, ordinarily five to ten different baths are necessary to achieve a satisfactory degree of cleanliness. When this degree of cleanliness has been reached and the liquid has been dumped for the last time through the valve 97, the shell 23 with the basket 24 is up-ended into the position shown in Fig. 1. In this up-ended position the basket 24 is rotated at extraction speed by the motor 70 to remove as much of the water which was absorbed by the clothes as is possible by centrifugal extraction.

A much greater economy results if the illustrated combined washer-extractor, instead of being used for the just described conventional washing method, is up-ended after each washing operation for a centrifugal extraction and the extracted liquid is drained off each time. This method requires, or at least renders favorable, the presence of the outlet opening 95 which assumes the position shown in Fig. 1 at the bottom end of the shell 23 when this shell and the basket are up-ended. The outlet opening 96 is either permanently kept closed or may be entirely dispensed with so that the washing liquid will not leave the shell as long as the same is in the horizontal washing position. Up to the time the shell and basket approach their vertical position the clothes are still floating in a pool of liquid so as to be better distributed in each sectional compartment of the basket for the following extraction operation than they would be if the liquid had been dumped while the shell and basket were still in the horizontal position. Now the basket 24 is rotated by means of the motor 70 at such a speed that the clothes which may have again a dry weight of 150 lbs. and which have absorbed at least 300 lbs. of liquid will contain after the extraction step only 150 lbs. of liquid. Consequently, the total weight of clothes plus absorbed liquid is 300 lbs., instead of the 450 lbs. which would be present prior to the second suds treatment according to the previously described conventional method. In the clothes there will be retained only approximately $\frac{1}{2}$ of the soil originally present as compared with the $\frac{3}{4}$ of the original soil left for the second suds treatment when the conventional method is used. Prior to the third liquid treatment there will be present, when the novel method is used, $\frac{7}{16}$ of the original soil as compared with $\frac{1}{16}$ of the original soil retained when the previously described conventional method is used. Expressed in terms of percentage, this means that after three treatments under the conventional method the soil contents in the clothes is about 45% of the original soil whereas with the new method, involving up-ending the washer each time a liquid treatment has been applied, the remaining soil contents is only 5%. It will be obvious therefore that with the latter method the number of the liquid treatments necessary for obtaining a desired degree of cleanliness is greatly reduced with corresponding savings in detergent and other materials.

Whereas the final extraction should be carried out at the full speed of the motor 70 in order to

remove as much liquid as possible prior to moving the clothes to the customary tumbler (drier), the above described extracting steps between the successive washing operations will ordinarily have a satisfactory effect already at an intermediate speed. Most of the liquid to be extracted in such an intermediate extraction step comes out an appreciable time before the basket has been brought up to full speed.

When the basket 24 is rotated, particularly at the high extraction speed, unbalance in the load with respect to the rotational axis will create at the level of the unbalance a positive force and a negative force of equal magnitude during each revolution. This level is at or near the resultant center of gravity of all the rotating parts. As has been described, the platform 12 is connected to the chains 18 at the upper ends of the upstanding arms 21 in a plane which at least approximately passes through said center of gravity of the combined rotating parts when the machine is in the vertical position. If the points at which the platform is linked to its suspensions are substantially above or below the plane in which the forces created by the unbalance develop then a moment would be created tending to cause the platform to develop a vertical component of motion which would be the larger the greater the distance of the plane in which the suspension points of the platform are situated from the center of gravity mentioned. Such vertical components of motion would cause the platform to jump or jiggle on the suspension links which would lead to a very undesirable and noisy type of vibration. Since according to the invention the center of gravity and the suspension points of the platform are situated in one and the same plane, practically no vertical vibrations will develop and the unbalances will cause no other movement of the platform 12 than swaying in the horizontal plane.

While I have shown in the drawing one particular embodiment of the invention, I desire it to be understood that this embodiment has been given by way of example only, and that various modifications and rearrangements of the details of the construction may be made without departing from the spirit of the invention or the scope of the appended claims.

What I claim is:

1. A laundry machine having, in combination, a cylindrical shell closed at one end, an open end cylindrical container supported on a shaft in line with the axis of said shell and turnably mounted in the closed end of said shell, a diametral partition dividing said container into two sections each open at the same end of the container, a door to close the open end of each section, a permanent closure for the lower half of the open end of said shell, two quadrant shaped plates swingable in a plane parallel to said closure and supported thereon adapted to close the remaining opening in the end of said shell, gears attached to each of said quadrants, a rack meshing with both of said gears.

2. A laundry machine having, in combination, a cylindrical shell, closed at one end, an open end cylindrical container supported on a shaft in line with the axis of said shell and turnably mounted in the closed end of said shell, a diametral partition dividing said container into two sections each open at the same end of the container, a door to close the open end of each section, a permanent closure for the lower half of the open end of said shell, two quadrant shaped plates swingable in a

plane parallel to said closure and supported thereon adapted to close the remaining opening in the end of said shell, gears attached to each of said quadrants, a rack meshing with both of said gears and hydraulic means supported on said permanent closure to simultaneously swing said quadrants to closed or open position by moving said rack.

3. A laundry machine of the type wherein a container for the work to be laundered is rotatably mounted in a shell and both said shell and container are movable from a horizontal washing position to a vertical extracting position, comprising, in combination, a stationary base, columns standing up from said base, a platform carrying said shell and said container, arms extending upwardly from said platform and coordinated each to one of said columns, linking elements adapted to bias said platform towards a specified position relative to said base extending each between a fixed point of one of said columns and the upper end of the platform arm coordinated to that column to permit a swaying movement of said platform relative to said base, the junction point between each upstanding platform arm and the coordinated linking element being situated in a horizontal plane approximately at the level of the center of gravity of said shell and all parts carried thereby in the vertical position of said shell, said shell being pivotally mounted on a horizontal axis extending substantially in said horizontal plane containing said junction points between said upstanding platform arms and said linking elements, two studs attached to points of said shell situated in a plane proximate to said horizontal plane which extends near said center of gravity, two posts on said platform, each of said two studs being pivotally mounted on one of said two posts so that said posts form two supports for said shell regardless of the position of the latter, and an outlet opening in that end wall of said shell which forms the bottom wall thereof when said shell is in vertical position, the position of said outlet opening in said end wall being such as to render said outlet opening ineffective for draining the shell when the latter is in the horizontal position.

4. A laundry machine of the type wherein a container for the work to be laundered is rotatably mounted in a shell and both said shell and container are movable from a horizontal washing position to a vertical extracting position, comprising, in combination, means partitioning said container diametrically into separate compartments for reducing the amount of unbalance of the load in said container, a stationary base, columns standing up from said base, a platform carrying said shell and said container, arms extending upwardly from said platform and coordinated each to one of said columns, linking elements adapted to bias said platform towards a specified position relative to said base extending each between a fixed point of one of said columns and the upper end of the platform arm coordinated to that column to permit a swaying movement of said platform relative to said base, the junction point between each upstanding platform arm, and the coordinated linking element being situated in a horizontal plane approximately at the level of the center of gravity of said shell and all parts carried thereby in the vertical position of said shell, said shell being pivotally mounted on a horizontal axis extending substantially in said horizontal plane containing said junction points between said upstanding

platform arms and said linking elements, two studs attached to points of said shell situated in a plane proximate to said horizontal plane which extends near said center of gravity, two posts on said platform, each of said two studs being pivotally mounted on one of said two posts so that said posts form two supports for said shell regardless of the position of the latter, and an outlet opening in that end wall of said shell which forms the bottom wall thereof when said shell is in vertical position, the position of said outlet opening in said end wall being such as to render said outlet opening ineffective for draining the shell when the latter is in the horizontal position.

5. A support for a washer having a cylinder rotatable in a shell in which the axis of rotation of both shell and cylinder are horizontal during washing and turned to the vertical during extracting comprising, a stationary base, columns rising from said base, links extending downward from the upper ends of said columns, a horizontal platform having arms extending upward from the platform to which said links are connected, two posts rising from said platform having bearings at the upper level of said upstanding arms, trunnions supported in said bearings whose axes are located in a plane at right angles to the washer axis which plane also contains the center of gravity of the washer and at some distance from the axis, and hydraulic means for turning said shell and cylinder into the horizontal position including at least one hydraulic cylinder bearing against a fulcrum carried by said platform, a piston reciprocable in each cylinder, at least one swing lever operated by said piston and adapted to bear against one end wall of said shell and dashpot means carried by said shell for preventing violent swinging of said shell about

the horizontal axis about which said shell and container are turnable.

6. In a cylindrical washer designed to permit extracting at high speed with the axis vertical and washing with the axis of the cylinder horizontal without loss of water at the loading end, in combination, a washer shell having one closed end, horizontal trunnions on the shell about which the washer shell can be tilted, a wall closing the lower half of the open end, two quadrant shaped doors pivoted on the wall, a rack movably carried by the wall, gears carried by the quadrant shaped doors meshing with the rack so that both quadrant shaped doors open simultaneously, a washing cylinder supported in the shell, an axial partition in said cylinder dividing the cylinder into a plurality of compartments each of which can be unloaded with the load resting on the partition, doors at one end of each cylinder compartment each of which is proximate to the quadrant shaped doors at some point in the rotation of the cylinder about its axis.
